UNITED STATES PATENT OFFICE.

IRA R. SELTZER, OF WATERBURY, CONNECTICUT, ASSIGNOR TO THE GORDON ELECTRIC MFG. CO., OF WATERVILLE, CONNECTICUT, A CORPORATION.

CONVERTIBLE ELECTRIC CORD SWITCH WITH PUSH-THROUGH CONTROL.

Application filed March 10, 1922. Serial No. 542,527.

To all whom it may concern:

Be it known that I, IRA R. SELTZER, a citizen of the United States, residing at Waterbury, in the county of New Haven and State 5 of Connecticut, have invented a new and useful Improvement in Convertible Electric Cord Switches with Push-Through Control; and I do hereby declare the following, when taken in connection with the accompanying 10 drawings and the characters of reference marked thereon, to be a full, clear, and exact description of the same, and which said drawings constitute part of this application, and represent, in—

15 Fig. 1 a view in elevation of a switch embodying my invention.

Fig. 2 a view thereof in central longitudinal section on an enlarged scale.

20 Fig. 3 a view of the switch with the casing removed.

Fig. 4 a corresponding view at a right angle to Fig. 3.

Fig. 5 a plan view of the switch with one cap removed.

25 Fig. 6 a reverse plan view thereof with the other cap removed.

Fig. 7 a detached perspective view of the main-line connecting bar.

This invention relates to an improved, 30 convertible, electric cord switch with push-through control, the object being to provide a simple, convenient and reliable switch constructed with particular reference to convertibility for insertion into a parallel wire 35 without removing the switch from the body of its case, but by cutting the wire, or, for insertion into a cord by cutting only one of the parallel wires and by passing the other wire through the switch for which 40 purpose the casing thereof must be removed.

With these ends in view, my invention consists in a switch having certain details of construction and combinations of parts as will be herein described and pointed out in 45 the claims.

In carrying out my invention as herein shown, I employ a switch-unit comprising a one-piece base 10, of insulating material, formed with a deep recess 11, for the reception 50 of a switch-mechanism of the rocker-type and comprising a frame 12, push-buttons 13 and 14, united by a screw 15, rocker or actuator 16, a circuit-opening-and-closing member 17, and a spring 18 therefor. This 55 switch-mechanism, which is well-known and

does not need detailed description, is secured within the base 10 by means of screws 19, countersunk in recesses 20 in one end of the base 10.

A plate 21, carrying a binding-screw 22, 60 forms the terminal of one side of the switch and is located in a recess 23 in one face of the base, and held in place by a long screw 24, the head of which passes through and holds in place the spring contact finger 25 65 of the switch-mechanism, the said finger coacting with the contact ear 26 of the circuit-opening-and-closing switch member 17 already referred to. A complementary ear 26^a, of the member 17, coacts with a complementary contact-finger 25^a, secured in place by being pinched between the base 10 and the inwardly-turned end 27 of a terminal plate 28, the outer end of which is bent 70 outwardly and carries a binding-screw 29, 75 which forms the terminal for the other side of the switch.

To provide for carrying the line current by the switch, the base 10 is provided with a longitudinal peripheral groove 30, which 80 adapts the switch-structure to be converted for use in either one or two ways as may be found most expedient. If it is desired to insert the switch in a cord without disassembling the switch by removing it from its cover or casing, which consists of a body or shell 31, provided with an insulating lining 32, and domical caps 33, having insulating linings 34 and insulating bushings 35, I may insert in the groove 30 an 90 angular, main-line connecting-bar or part 36, carrying binding-screws 37 and 38, at its opposite ends, in the groove 30 and retained in place by its shape and by the entrance of its said binding-screws into 95 clearance-pockets 39 formed in the base at its ends with integral extensions standing at a right angle to its longitudinal axis and respectively carrying binding-screws 37 and 38. These extensions virtually embrace the opposite ends of the chambered 100 cylindrical base 10 and prevent the longitudinal displacement of the bar 36 in the groove 30, in which it is held against lateral displacement by the said binding-screws and also by the lining 32 of the shell 31, which 110

closes in the open side of the said groove. When the part 36 is employed in the manner described, both of the parallel wires of the cord are cut and their ends attached to 5 the terminal screws 22 and 38 at one end, and 29 and 37 at the other end, this being done without removing the shell of the casing from which it is necessary only to 10 remove the caps 33. On the other hand, if it is desired to preserve the continuity of one of the parallel wires for the strength 15 it gives to the installation, or for any other reason, the connecting-bar or part 36 may be omitted, or removed if present, when the groove 30 becomes available for the passage by the switch of one of the two parallel wires which is left uncut. The 20 ends of the other wire, which is cut, are then connected with the binding-screws 29 and 22.

I claim:

1. In a convertible electric cord-switch with push-through control, the combination 25 with a cylindrical shell, of a chambered cylindrical base of insulating material located therein and formed in its periphery 20

with a longitudinal groove extending between its ends, a switch-mechanism mounted in the said base, and a removable main-line connecting-bar located in the said groove 30 and adapted to embrace the said base, by which it is held against longitudinal displacement with respect thereto.

2. In a convertible electric cord-switch with push-through control, the combination 35 with a cylindrical shell, of a chambered cylindrical base of insulating material located therein and formed in its periphery with a groove extending between its ends, 40 of a switch-mechanism mounted in the said base, and a removable main-line connecting-bar located in the said groove and formed at its respective ends with extensions arranged at a right angle to its axis and carrying binding-screws entering the said 45 base, whereby the said bar is held against lengthwise displacement with respect to the base by its said extensions and against lateral displacement with respect to the base by the entrance of the said binding-screws 50 thereinto.

IRA R. SELTZER.
